UNITED STATES PATENT OFFICE.

HARRISON D. BOYER, OF FERNROCK, PENNSYLVANIA, ASSIGNOR TO BOYER MANUFACTURING COMPANY, A CORPORATION OF NEW JERSEY; S. STANGER ISZARD, RECEIVER, OF WOODBURY, NEW JERSEY.

LUBRICATOR.

1,292,692.

Specification of Letters Patent.

Patented Jan. 28, 1919.

Application filed April 4, 1916. Serial No. 88,933.

To all whom it may concern:

Be it known that I, HARRISON D. BOYER, a citizen of the United States, residing at Fernrock, in the county of Philadelphia and 5 State of Pennsylvania, have invented new and useful Improvements in Lubricators, of which the following is a specification.

My invention relates to new and useful improvements in the method of feeding lubricant to bearings and the devices for carrying the same into effect, and has for its object to accomplish this result by driving a hollow plug into the body of the lubricant so as to displace a portion of said lubricant, 10 and thereafter gradually force the displaced portion of the lubricant from the hollow plug, so as to bring about the feeding of the lubricant to the bearing, and a further object of my invention is to provide a simple and 15 effective mechanism for accomplishing this result, which is here shown as being especially adapted for the class of grease cups known as locomotive grease cups.

With these ends in view, my invention 20 consists in the details of construction and combination of elements hereinafter set forth and then specifically designated by the claims.

In order that those skilled in the art to 25 which this invention appertains, may understand how to make and use the same, I will describe its construction in detail, referring by numerals to the accompanying drawings forming a part of this application, in 30 which—

Figure 1, is a central vertical section of a 35 locomotive grease cup, showing my improvement applied thereto, the parts being in the position they assume when the cup is full of grease and the plug driven therein.

Fig. 2, is a similar view showing the plug in its lowest position and the plunger in dotted lines at its lowest position, or after all of the displaced grease has been fed from 40 the plug.

Fig. 3, is an elevation of the plug, showing the plunger rod thereof held in place by a cotter pin.

Fig. 4, is a plan view of Fig. 3.

Fig. 5, is a side elevation of the cup shown in Figs. 2 and 3, illustrating a slightly modified form of signal, and also embodying a lock to hold the plug against retrograde movement.

Fig. 6, is a plan view of Fig. 5. 55

Fig. 7, is a broken away section of a portion of the plug and plunger rod, showing a slightly modified form of the means for throwing the signal.

Fig. 8, is a view similar to Fig. 7, showing 60 a still further modification of the means for throwing the signal.

Fig. 9, is a view similar to Fig. 7, showing a modified form of signal; and

Fig. 10, is a view similar to Fig. 9, showing 65 a slightly modified form of the last named signal.

In carrying out my invention as here described, I provide a lubricant receptacle 1, which may be of any desirable design, here 70 shown as a grease cup cast with the strap 2. This receptacle is entirely closed by the cap 3 with the exception of the feed outlet 4, by which the lubricant is fed to the bearing. Through this cap the plug 5 is screwed so 75 as to be driven into the lubricant which entirely fills the interior of the receptacle. Within the plug is fitted a spring actuated plunger consisting of a head 6 formed with the body 7 or secured thereto, a packing 8 80 and a loose washer 9 slipped over the rod, so as to be forced against the packing by the spring 10.

To the upper end of the body is attached a semaphore signal here shown in the form 85 of a ring 11, which when the device is in feeding position, will lie out of signal position as shown in Fig. 1, but when the device has reached the limit of its feed, will be thrown into signal position as shown in 90 Fig. 2.

In carrying out my method of feeding lubricant to a bearing by the devices just described, the receptacle is packed full of grease, the cap 3 screwed home after which 95 the plug is driven into the body of the grease, displacing a portion thereof, the displaced portion of the grease rising in the interior of the plug and forcing the spring actuated plunger upward, thereby putting a 100 strong spring pressure upon the entire grease contained within the receptacle, which pressure will cause the grease to be fed from the receptacle through the feed outlet 4 to the bearing, and as this feeding 105 continues the plunger will gradually fall, ejecting the displaced grease from the plug until at the finished ejection of this grease,

the semaphore 11 will be thrown into signal position indicating that the device needs resetting. To reset the device after the semaphore has been thrown to signal position, it is only necessary to screw the plug farther downward, again displacing a portion of the grease within the receptacle and causing it to rise within the plug.

When the plug has been set and reset until it reaches its lowest position illustrated in Fig. 2, and the semaphore has been thrown to signal position, indicating that all of the grease has been ejected from the plug, the plug is backed out of the cap, and that portion of the lubricant which has been displaced by the plug during the various settings thereof is replenished by inserting a fresh supply of lubricant, and in the case of locomotive cups, here shown, the grease used is a solid material and consequently a cavity will be left in the center of the contents of the cups when the plug is withdrawn, corresponding to the size of the plug, and the replenishing of the cup will be accomplished by inserting the lubricant in the form of sticks or cartridges as is the present day practice with this class of cups. After the cup has been replenished the plug is again threaded through the cap and forced into the body of the lubricant to displace the same as before described.

It is to be noted that the actions of the plug and its plunger can never feed the entire contents of the cup to the bearing, and this is a feature of importance in this class of cups, since that portion of the lubricant which cannot be fed by the action of the plug and its plunger forms a reserve of lubricant, which in case of the bearing becoming unduly heated will be melted to a sufficient extent to permit it to flow to the bearing, thus flushing the same and holding its temperature within the limit of safety.

Heretofore the usual practice has been to fill this class of cup full of exceedingly hard grease having a relatively high melting point and depending entirely upon the heat generated by the friction of the bearing to partially melt and burn down the lubricant, but while this has proven fairly satisfactory because it provides for the flushing of the bearing, should it become overheated, yet it has been objectionable because the bearing had to rise in temperature to a point tending to wear the bearing, but by my improved method the lubricant is always put against the bearing without regard to the temperature thereof, and yet should from any cause the bearing unduly increase in temperature the reserve lubricant will be melted and flush the bearing as in the present day practice, thus giving a two fold or duplex function to my improvement.

In Figs. 3 and 4 I have shown the plunger rod 7 as being provided with a cotter pin 12

to prevent its ejection from the plug by its spring.

In Figs. 5 and 6 I have shown a slightly modified form of semaphore signal which consists of a U shaped strap 11, which is pivoted to the rod 7 by a cotter pin 13, and this strap is provided with lugs 14 acting as cams by which it is caused to rise from out of signal position to signal position by contact with the top of the plug 5, as will be readily understood. Also in these last named figures I have shown a means for locking the plug against retrograde movement, after it has been set, and this means consists of a spanner wrench 15 pivoted to the cap 3, its nose being adapted to latch into the holes 16 formed in the plug. This lock while being shown as forming approximately a quarter of a circle around the plug may extend around the same a half circle or more.

By the use of this form of locking device the necessity for the lock nut 17 is obviated and the plug will be held more securely against retrograde movement than is possible when a lock nut is used, and this is of considerable importance in locomotive work, where the jar and vibration is intense.

In Fig. 7 I have shown a slightly modified form of means for throwing the ring semaphore to signal position, which consists in substituting for the recess 18 shown in the top of the plug in Fig. 1, a thimble 19 which fits over the top of the rod 7 having holes 20 therein for the passageway of the ring 11. The holes 20 are of sufficient size to permit the swinging of the ring 11 when moving from one position to another. As the rod moves downward the bottom of the thimble will come in contact with the upper surface of the plug, and any further downward movement of the rod will cause the ring to be thrown to signal position as shown in this figure.

In Fig. 8, the signal throwing device is slightly modified in which case a ring 21 is substituted for the thimble 19, and lies around the rod 7 beneath the semaphore 11, so that as the rod falls, it will throw the semaphore to signal position as shown.

In Fig. 9 I have shown a slightly modified form of signal which consists of a member 22 fitted to slide in the top of the rod 7 and into which a pin 23 of any desirable shape is secured, the ends of said pin projecting through the openings 24 in the sides of the rod, so that when said rod approaches its lowest position, the pin 23 will come in contact with the upper surface of the plug 5, arresting the downward movement of the member 22, while permitting the rod a further limited movement which will cause the member 22 to protrude above the top of the rod; and in practice this member should be enameled a different color from the rod, 130

or made of a material of different color such as red, so that when projecting above the top of the rod it will signal the fact that the cup has finished feeding and needs resetting.

- 5 In Fig. 10 I have shown a slightly modified form of signal shown in Fig. 9 which consists in placing a band 25 or its equivalent around the top of the rod and securing it to the rod by a pin 26 or its equivalent 10 in such manner as to give the collar a limited movement upon the rod.

In this construction when the rod approaches its lowest position the collar coming in contact with the top of the plug 5 will 15 be stopped in its downward movement, while the continued downward movement of the rod will cause the end of said rod to disappear below the upper surface of the collar, thus indicating that the cup needs resetting, 20 and to make this fact prominent I prefer to notch or serrate the upper edge of the collar as shown. While I have designed and used many other forms of signals for lubricators, I deem the herein showing sufficient to illustrate 25 my invention in this respect but do not confine said invention to this showing.

I have described my improved devices as standing in a vertical position, but it is obvious that they may stand at any angle, and 30 perform their functions.

Of course I do not wish to be limited to the exact details of construction as herein shown, as these may be varied within the limits of the appended claims without departing 35 from the spirit of my invention.

Having thus fully described my invention, What I claim as new and useful, is—

1. In combination with a lubricator casing having a centrally apertured closing cap 40 and a basal feed outlet, a hollow plug of relatively lesser diameter and length removably mounted in said casing, and a spring actuated plunger mounted to reciprocate in said hollow plug, whereby the contained 45 lubricant will be automatically fed under pressure through said basal outlet to the bearing.

2. In combination with a grease cup having an open top and a basal feed outlet, a 50 hollow plug of relatively lesser diameter

and length, means adapted to close the top of said casing and to removably support said plug within the cup, and a spring-actuated plunger mounted to slidingly reciprocate within said hollow plug and operating to automatically eject the contents thereof.

3. A feed mechanism for lubricators having a cap threaded thereon and a hollow plug threaded through the cap in such manner as to be driven into the body of the contents of the lubricator, a spring actuated plunger fitted in the plug, and a signal connected with the plunger in such manner as to be thrown into signal position when the plug needs resetting.

4. A feed mechanism for lubricators having a cap threaded thereon and a plug threaded through the cap, a spring actuated plunger fitted to slide in the plug, a rod 70 extending from the plunger to the top of the plug, and a signal attached to the upper end of the rod and adapted to lie out of signal position when the plunger is feeding the lubricant, and be thrown into signal position when the feeding terminates.

5. A feed mechanism for lubricators having a cap threaded thereon and a plug threaded through the cap, a spring actuated plunger fitted to slide in the plug, a rod 80 extending from the plunger to the top of the plug, and means for limiting the downward movement of the rod.

6. In combination with a grease cup, a feed mechanism consisting of a hollow plug 85 threaded through the top of said cup, said plug being of smaller diameter than the inside diameter of the cup, whereby a large space for reserve grease is provided, a spring actuated plunger fitted to slide in the plug 90 and means connected with the plunger for throwing a signal when the grease stops feeding.

In testimony whereof, I have hereunto affixed my signature in the presence of two 95 subscribing witnesses.

HARRISON D. BOYER.
